Frank N.L.Willett

By *Myself*

UNITED STATES PATENT OFFICE.

FRANK N. L. WILLETT, OF AURORA, ILLINOIS.

SHEEP-SHEARS.

1,348,914.

Specification of Letters Patent. Patented Aug. 10, 1920.

Application filed September 19, 1919. Serial No. 324,751.

To all whom it may concern:

Be it known that I, FRANK N. L. WILLETT, a citizen of the United States, and a resident of Aurora, in the county of Kane and State 5 of Illinois, have invented certain new and useful Improvements in Sheep-Shears; and I do hereby declare that the following is a full, clear, and exact description thereof, reference being had to the accompanying 10 drawings, and to the letters of reference marked thereon, which form a part of this specification.

This invention relates to sheep shears and particularly to that class of shears which are 15 hand directed and power driven. Devices of this character include a comb or stationary cutter fixed to a casing or housing, a vibrating cutter, a vibrating lever for operating said cutter and means for applying pressure to the vibrating cutter to hold the same 20 in close contact with the stationary cutter.

The particular object of my present invention is to improve the shears, of this general class, shown in my prior Patent No. 25 896,497, of August 18, 1908, wherein an oscillating arm vibrates a cutter across a stationary cutter or comb several thousand times each minute, with the result that there 30 is a great tendency of the parts to become worn or loosened in use. This results in the bearing surfaces of the presser fingers which bear on the top of the cutter not only becoming worn but often times becoming worn unevenly, thus making the presser fingers bear 35 unevenly upon the vibrating cutter and impairing its efficiency.

It will also be noted that the vibrating cutter is provided with apertures into which pins, depending from the vibrating head, 40 project. The vibration causes wear and loosening of these pins. The result is that in practice these pins have to be removed and new ones inserted very frequently—sometimes as often as every other day during 45 the shearing season. Furthermore, the wear on the presser fingers themselves is such that they have to be frequently removed and new ones inserted. These parts are costly: For example, a cutting tool of the type referred to, costing, say \$15.00 will require 50 during the four months shearing season, a dozen pairs of presser fingers at an expense of approximately \$6.00, and new pins connecting the vibrating arm with the vibrating cutter, at an expense of about \$3.00, in addition to the expense and time required to

remove the pins from the vibrating arm, inserting the new ones, and riveting the same to the arm. It has been found impractical to regrind the presser fingers after they become worn, on account of the difficulty in restoring them to their proper position so as to contact with the vibrating cutter, and for this reason new presser fingers are generally used when the old ones become worn. 60

To remedy these practical difficulties and save the expense of repair parts and to make a better and more satisfactory sheep shears, are the principal objects of my invention.

In the drawings:

Figure 1 is a top plan view of a sheep shearing machine embodying my invention.

Fig. 2 is a vertical, longitudinal, sectional view of the same taken on the plane of its longitudinal axis.

Fig. 3 is a bottom plan view of the vibrating arm.

Fig. 4 is a plan view of the vibrating cutter.

Fig. 5 is a front view of two of the teeth 80 of the vibrating cutter with a pair of the presser fingers in position thereon, slightly enlarged.

Fig. 6 is a sectional view, enlarged, of two of the teeth of the vibrating cutter and 85 a pair of presser fingers, taken on the line 6—6 of Fig. 2, looking in the direction indicated by the arrow.

Fig. 7 shows a modification.

In that form of device embodying my invention, illustrated in the drawings, 1 indicates the ordinary housing terminating in the handle 2. A comb or stationary cutter 3 is securely fixed to the bottom of the housing 1. The vibrating cutter 4 is provided 90 with four cutting teeth 5, having outwardly and downwardly sloping or flaring sides 5^a as shown.

The vibrating lever or arm is indicated at 6, and is fulcrumed at the ball and socket 100 joint 7 and driven by a crank or eccentric 8, fixed upon the end of the shaft 9. The vibrating arm 6 is removably attached to the cutter 4 as will be hereinafter described, and pressure is applied thereto by means of the 105 dolly-pin 10 and the tension screw 11.

The vibrating arm 6 is provided with a head 12 of practically the same width as the cutter 4. In the ends of the head 12 I provide pins 13 which enter holes 14 in the cutter 4. The pins 13 aid in transmitting the vibratory motion of the arm 6 to the cutter 110.

4 and hold these parts in proper relation with respect to each other.

Presser fingers 15, arranged in pairs, are connected by a yoke 16, having a stem 17, by which it is mounted in the head 12 of the vibrating arm 6. The stems 17 are preferably arranged in lines extending radially from the fulcrum point of the lever or arm 6, which is free to swing or turn upon a longitudinal axis defined by the ball and socket joint 7 and the ball 10 on the end of the dolly-pin. The presser fingers 15 are provided on their outer ends with notches 20, adapted to contact with the sloping sides 5^a of the cutting teeth 5.

These notches 20 straddle the cutter to permit the presser fingers 15 to contact with the sides of the cutting teeth and exert side-wise pressure thereon. These notches are shown as V-shaped, but it will be understood that any other form of notch may be used, as for example, the form shown in Fig. 7.

It will be noted that in devices of the character heretofore known, and such as shown in my patent hereinabove referred to, the transmission of the vibratory motion from the arm 6 to the cutter 4 has been accomplished solely by means of the pins 13 projecting into the holes 14 of the cutter 4,—the pressure fingers 15 acting merely to bear upon the top of the cutter teeth and hold the cutter down upon the stationary comb or cutter 3.

In my improved device, I have made the presser fingers 15 in such form as to secure not only the bearing effect upon the cutter 4, referred to, but also to engage with the sides of the associated cutter teeth 5, whereby the

strain of transmitting vibratory motion is almost entirely removed from the pins 13 and evenly distributed to the four presser fingers 15, and through them motion is transmitted to the cutter teeth.

I find in practice that a machine embodying my present invention may be used during an entire shearing season without the necessity of renewing either the pins or the presser fingers, as had heretofore been required,—thereby effecting a great saving of money and labor to the user.

I claim as my invention:

In a sheep shearing machine having a stationary and a vibrating cutter and an operating arm for oscillating the vibrating cutter, said vibrating cutter being provided with a plurality of teeth each having outwardly and downwardly flaring side walls, and also provided with openings at each end, a pair of pins carried by said operating arm and adapted to seat in the openings in said vibrating cutter and thereby connect said arm with said cutter, and a plurality of presser and operating fingers loosely mounted in pairs on said operating arm, each presser finger having means on its outer ends adapted to engage the flaring sides of a cutter tooth and thereby prevent transverse and vertical movement.

In testimony, that I claim the foregoing as my invention I affix my signature in the presence of two witnesses, this 15th day of September A. D. 1919.

FRANK N. L. WILLETT.
